UNITED STATES PATENT OFFICE.

IEREMIE IRINA, OF DAYTON, OHIO.

SMOKE-DISPENSER.

1,301,563.

Specification of Letters Patent. Patented Apr. 22, 1919.

Application filed June 4, 1918. Serial No. 238,163.

To all whom it may concern:

Be it known that I, IEREMIE IRINA, a citizen of the United States, residing at Dayton, in the county of Montgomery and State 5 of Ohio, have invented new and useful Improvements in Smoke-Dispensers, of which the following is a specification.

The object of the invention is to provide simple and efficient means adapted to be carried by vehicles for use on water or land, for producing and dispensing a concealing screen of smoke or vapor, which may or may not be of a poisonous character, as a source of protection against an enemy. The idea 10 has been conceived of enveloping a ship at sea with a cloud of smoke or vapor so as to conceal it from the occupants of an enemy craft, with a view to minimizing the risk of injury by torpedoes, gun fire and the like, by rendering the mark invisible, and the object 15 of the present invention is to provide efficient means for carrying out this idea, not only with reference to vessels at sea, but also troop, munition and supply trains within 20 the war zone on land.

Further objects and advantages of the invention will appear as the description is developed, it being understood that only the essential features are disclosed and that various changes in detail may be resorted to, in the adaptation of the same to different types and styles of vehicles or means of conveyance, and different conditions of use and special requirements, without departing 35 from the spirit of the invention.

In the drawing:—

Figure 1 is a side view partly in section of an apparatus embodying the invention applied to a ship.

Fig. 2 is a plan view of the same.

Fig. 3 is a side view of an embodiment of the apparatus applied to a troop or similar train.

Fig. 4 is a longitudinal sectional view of the generator by means of which a dense smoke is provided for use in the apparatus.

In the construction illustrated, more especially in Figs. 1 and 2, a conductor 10 is employed, extending, for example, longitudinally of the vehicle, such as a ship, and provided at its extremities and at suitable intermediate points with outlets or dispensing nozzles 11 and 12, adjustable valves or deflectors 13 being employed at the intersec-

tions of the various elements to enable the operator to direct all or a greater portion of the discharge through one nozzle or another, or to cut off one or more of the same as may be required. These discharge nozzles or outlets may be located at both ends of the vehicle, and communicating with the conductor at an intermediate point is a supply drum 14 into which discharges a generator 15, which may be of any suitable type adapted to produce a dense smoke, or produce a gas adapted on exposure to the air to produce a dense smoke, and which may if desired embody a poisonous or irritant gas or vapor to add to the confusion of the enemy whether in front or in rear of the vessel. To insure the forcible discharging of the smoke or vapor, blast fans 16 may be employed, the casing 17 thereof being in communication with air tubes 18 which may draw a supply from above the vessel at an intermediate point, as shown. At the point of communication of the drum 14, into which the blast fans discharge, with the conductor, may be arranged a deflector or valve 19 which may be adjusted to direct the supply of smoke or other vapor either forwardly or rearwardly. Also a suitable elevated lookout 20 may be employed as a means of protecting the officer in charge from the effects of the discharge from the apparatus. When, as indicated in Fig. 3, the device is applied to a land vehicle, such as a train, a similar arrangement may be utilized with more or less modification, but in this case the furnace of the engine indicated at 21 may be utilized as the generator for the smoke or poisonous gas, or both, a blast fan 22 being employed to induce a draft which serves not only to discharge the vapor at the forward end of the train but to support combustion in the engine furnace, or fire-box. Also auxiliary air inlets 23 may be employed, especially when the admixture of air with the vapor discharged by the generator is necessary to produce the desired effect in the matter of forming a dense 90

cloud or concealing curtain.

What is claimed is:—

In an apparatus for the purpose specified, the combination with a transportation vehicle, of a smoke stack disposed substantially in a horizontal plane and extending throughout the length of the vehicle, the said stack

having fork terminals both at the forward and rear ends of the vehicle, valves adjacent the forks by which smoke passing through the stack may be directed through any leg of the fork, a smoke generating means by which smoke may be discharged into the stack, and a valve in the stack adjacent the

point where it communicates with the smoke generating means whereby the smoke from said means may be directed to one or the other of the forked terminals. 10

In testimony whereof I affix my signature.

IEREMIE IRINA.
